DESIGN FOR SUSPENDERS

Philip Ginsberg, Brooklyn, N. Y.

Application August 24, 1945, Serial No. 121,597

Term of patent 3½ years

(Cl. D17—15)

To all whom it may concern:

Be it known that I, Philip Ginsberg, a citizen of the United States of America, residing at Brooklyn, in the county of Kings and State of New York, have invented a new, original, and ornamental Design for Suspenders, of which the following is a specification, reference being had to the accompanying drawing, forming a part thereof.

In the drawing:

Figure 1 is a perspective view of suspenders, showing my new design, the rear of the same presenting substantially the same appearance as the front, except as indicated in Figure 2.

I claim:

The ornamental design for suspenders, as shown and described.

PHILIP GINSBERG.
